UNITED STATES PATENT OFFICE.

GEORGE A. LOGAN, OF CAMBRIDGE, MASSACHUSETTS.

SAFETY-RAZOR.

968,578.

Specification of Letters Patent. Patented Aug. 30, 1910.

Application filed December 3, 1909. Serial No. 531,142.

To all whom it may concern:

Be it known that I, GEORGE A. LOGAN, of Cambridge, in the county of Middlesex and State of Massachusetts, have invented an Improvement in Safety-Razors, of which the following is a specification.

This invention relates to safety razors of that type wherein the blade is held in fixed position between a front plate adapted to 10 serve as a guard, and a back plate, said plates being arranged on the end of a hand-piece by which the implement may be manipulated.

The invention has for its object to construct improved forms of back and front plates, which are hinged together at their upper edges, and adapted to hold a blade very securely between them, and also in correct position for use; also to construct an 20 improved form of detachable hand-piece and clamping-screw thereon, by which the back and front plates are held in fixed position with the blade between them.

Figure 1 is a side elevation of a safety 25 razor embodying this invention, Fig. 2 is a plan view of the same, Fig. 3 is an under side view of the same, Fig. 4 is an enlarged vertical longitudinal section of the same taken on the dotted line 4—4, Fig. 2, Fig. 30 5 is a view of the hinged plates shown in open position, Fig. 6 is a vertical section of the plates shown in Fig. 5, taken on the dotted line 6—6, Fig. 7 is an under side view of the head of the clamping-screw on 35 the hand-piece, showing particularly a boss thereon which enters recesses formed in the plates, Fig. 8 is a detail showing the permanently magnetized hand-piece and a razor-blade attracted by it, Fig. 9 is a view 40 of the hinged plates in open position showing modified means for holding the blade, Fig. 10 is a vertical section of the hinged plates shown in Fig. 9, Fig. 11 is a view of the blade which is employed in connection 45 with the hinged plates shown in Figs. 9 and 10.

a represents the front plate and *b* the back plate. Said plates are made rectangular in shape and are hinged together at 50 one edge by hinges *c*, *c*.

As a simple form of hinge which may be easily and cheaply made the plate *a* has slots *c* horizontally arranged near its upper edge, two being here shown, and the plate *b* 55 has ears *c*, one of which is broken off in Fig. 5, made of a width corresponding to the

length of the slots, which are bent circularly around the narrow portions of the plate between the slots and the edge of the plate. The edge of the plate *b* also has curved 60 lips *b*', *b*', at each side of the ears *c*', which extend over the edge of the plate *a*.

By means of the hinges the plates *a* and *b* are held fixed in all positions relative to each other, except permitting them to move 65 toward and from each other.

The front-plate *a* comprises two substantially flat portions *a*', *a*², extending from end to end thereof and arranged to form an obtuse angle. The lower edge of the portion 70 *a*' is formed with teeth *a*³, which are made quite long to provide long interdental spaces *a*⁴; the length of the teeth, however, is not as material as the length of the interdental spaces, as the latter afford recesses for the 75 bristles and lather. The toothed portion *a*' of the plate serves as a guard. The upper edge of the portion *a*² has the slots *c* for the hinge connections, and also has a transverse recess *d* at the middle, extending inwardly from its edge, substantially its full width, so that said recess terminates close to the apex of the angle formed by the two portions *a*', *a*², of the plate. Said recess *d* 80 has parallel sides and a rounded end. The 85 back-plate *b* likewise comprises two substantially flat portions *b*², *b*³, extending from end to end thereof and arranged to form an obtuse angle.

The width of the flat portion *b*² is less 90 than the width of the flat portion *a*' of the plate *a*, so that the teeth of the said plate *a* project beyond the edge of the plate *b*. The width of the flat portion *b*³ is substantially 95 the same as the width of the flat portion *a*² of the plate *a*, and the obtuse angles of both plates are approximately the same, so that when the plates are caused to approach each other they may engage each other throughout their length or over all. The upper 100 edge of the flat portion *b*³ has the ears *c* for the hinge connections, and also the lips *b*', and it also has a transverse recess *d*', corresponding in shape, size and position to the recess *d* in plate *a*, so as to register 105 therewith when the two plates are closed together.

The plate *a* may have spurs *e*, *e*, at the ends to enter recesses formed in the ends of the razor-blade *f*, to thereby correctly position the blade with respect to the plates. 110

As shown in Figs. 2 and 3, the ends of the

plate *b* are cut away, as at *e'*, *e'*, permitting the plate *b* to be closed upon the plate *a*, although said recesses *e'*, *e'*, perform no other function.

5 The razor-blade *f* is placed between the spurs *e*, *e*, on the flat portion *a'* of the plate *a*, and then the plate *b* is closed down upon it, thereby engaging it and holding it in position.

10 In lieu of providing the blade-engaging portion *a'* of the plate *a* with spurs *e'*, said portion, near the apex of the angle in the plate, may have a narrow slot or elongated recess *e''* see Figs. 9, 10 and 11 extended from 15 nearly end to end of the plate, adapted to receive the rear edge of a blade *e¹²* formed with beveled ends, *e¹³*, said beveled ends engaging the end walls of the slot, as shown to thereby correctly position the blade; and 20 said slot is so arranged that when the blade is projected into it the cutting-edge thereof will be lifted slightly above the flat portion of the plate; or, in other words, the blade is held obliquely to the plane of the plate, 25 and, when the plate *b* is closed down upon the plate *a*, said blade will be engaged and bent transversely to a slight extent to bring its cutting-edge into correct position at the toothed edge of the plate.

30 For the purpose of securely holding the plates in closed position and also to provide means for manipulating the implement, a hand-piece is provided, having a clamping-screw at the end. Said hand-piece is here 35 shown as composed of two short cylindrical bars *g*, *g'*, screwed or otherwise connected together, to thereby produce a hand-piece of suitable length, and the end of the bar *g'* has a screw-threaded socket *g²*, which receives the clamping-screw *g³*. The head *g⁴* of the clamping-screw is circularly formed and has on its under side a boss *g⁵*, made with parallel sides and a rounded end. Said boss *g⁵* is of a shape to substantially fit the 40 recesses *d*, *d'*, in the plates, and is made of a thickness corresponding approximately to the thicknesses of both plates, and, when contained in said recesses, will hold the clamping-screw from turning with the circularly-formed head *g⁴* arranged at the back side of 45 the back plate and the hand-piece at the front side of the front plate. By then turning the hand-piece to revolve it on the clamping-screw *g³*, said hand-piece and 50 clamping-screw will be drawn toward each other to thereby clamp the plates between them:

When the hand-piece is secured to the plates it will be seen that the blade will be held at the correct angle for use, owing to forming the plates angularly as shown. The portion *g* of the hand-piece may be permanently magnetized so that it may be employed as a means of taking the razor blades

from a box and for placing them in the box, 65 as represented in Fig. 8.

I claim:

1. In a safety razor, a pair of plates hinged together at their upper edges, the lower edge of one of said plates extending 70 beyond the corresponding edge of the other plate and having a row of teeth, recesses extending inwardly from the upper edges of said plates, intermediate their length, which register with each other when the plates are 75 in closed position, a hand-piece, and clamping-means for the plates connected with said hand-piece which enter both of said recesses, substantially as described.

2. In a safety razor, a pair of obtuse-angled plates, hinged together at their upper edges by a pair of hinges, each plate comprising a flat attaching-portion and a flat blade-engaging portion, the edge of the blade-engaging portion of one of said plates 85 extending beyond the corresponding edge of the other plate and formed with a row of teeth, and the attaching portions of both plates being recessed, a hand-piece having a flat engaging-face to engage the attaching-portion of the under plate, between the 90 hinges, and a clamping screw connected with said hand-pieces adapted to enter the recesses in the attaching-portions of the plates, and having a head with a flat engaging-face to engage the attaching-portion of the upper plate, between the hinges, said head extending forward approximately to the bend of the plate, substantially as described.

3. In a safety-razor, a pair of obtuse-angled plates hinged together at their upper edges, the lower edge of one of said plates extending beyond the corresponding edge of the other plate and formed with a row of teeth, recesses formed in said plates at their upper edges, which register with each other when the plates are in closed position, a hand-piece, a clamping-screw on said hand-piece, having a boss which enters said recesses and having a head which engages the back side of the back-plate while the hand-piece engages the front side of the front plate, to thereby securely hold the two plates in closed position with a blade between them 115 and to attach said plates to the hand-piece, substantially as described.

4. In a safety-razor, a pair of obtuse-angled plates hinged together at their upper edges, each plate having two substantially 120 flat portions, the lower edge of one plate extending beyond the corresponding edge of the other plate and formed with a row of teeth, the upper flat portions of both plates having transverse recesses mid-way their 125 length, extending from their upper edges inwardly approximately their full width, a hand-piece, a clamping-screw on the hand-

piece, having a boss shaped to correspond to the shape of the recesses which enters said recesses, and having a head which engages the back side of the back-plate while the end of the hand-piece engages the front side of the front-plate, to thereby securely hold the two plates in closed position with the blade between them, and to attach the plates to the hand-piece and prevent the same from turning with respect thereto, substantially as described.

5. In a safety-razor, a pair of obtuse-angled plates hinged together at their upper edges, the lower edge of one of said plates 15 extending beyond the corresponding edge of the other plate, and formed with a row of teeth, elongated recesses formed in said plates at their upper edges, which register with each other when the plates are in closed position, a hand-piece, a clamping-screw on said hand-piece, having an elongated boss corresponding to the shape of the recesses in the plates which enters said recesses and having a head above the boss which engages the 25 back side of the back-plate while the end of the hand-piece engages the front side of the front-plate, to thereby securely hold the assembled parts in fixed relative positions, with a blade securely held between the obtuse-angled plates, substantially as described.

6. In a safety-razor, a pair of obtuse-angled plates hinged together at their upper edges, each plate having two substantially

flat portions, the lower edge of one plate extending beyond the corresponding edge of the other, and formed with a row of teeth, the front plate having a narrow elongated slot arranged obliquely to the plane of the plate, which receives the rear edge of the blade to hold said blade obliquely to the plane of the plate in order that it may be bent into correct position by the back-plate closing upon it, substantially as described.

7. In a safety-razor, a pair of obtuse-angled plates hinged together at their upper edges, each plate having two substantially flat portions, the lower edge of one plate extending beyond the corresponding edge of the other, and formed with a row of teeth, the front plate having a narrow elongated slot arranged obliquely to the plane of the plate, which receives the rear edge of the blade, to hold said blade obliquely to the plane of the plate in order that it may be bent into correct position by the back-plate 55 closing upon it, and a blade having beveled ends which engages the ends of said slot, to thereby correctly dispose it relative to the plate bearing it, substantially as described.

In testimony whereof, I have signed my 60 name to this specification, in the presence of two subscribing witnesses.

GEORGE A. LOGAN.
